ATTORNEYS

UNITED STATES PATENT OFFICE.

DAVID L. KEELER, OF GRAND RAPIDS, MICHIGAN.

TOY SWING.

SPECIFICATION forming part of Letters Patent No. 449,938, dated April 7, 1891.

Application filed September 24, 1890. Serial No. 366,038. (No model.)

To all whom it may concern:

Be it known that I, DAVID L. KEELER, a citizen of the United States, residing at Grand Rapids, in the county of Kent and State of Michigan, have invented certain new and useful Improvements in Toy Swings; and I do hereby declare the following to be a full, clear, and exact description of the invention, such as will enable others skilled in the art to which it appertains to make and use the same.

My invention relates to a toy swing; and it consists in the construction, combination, and arrangement of the parts hereinafter described, and pointed out in the claims, reference being had to the accompanying drawings, wherein—

Figure 1 is a perspective of a device embodying my invention, and Figs. 2 and 3 detached details.

A represents a table or board to which the device is attached.

The structure is preferably of wire, and has a frame formed of a single continuous piece of wire bent at right angles at various points to form, respectively, the side posts B, top B', and bottom B'', the parts being secured together by a band or coil C where they branch apart to form a base or foot portion for supporting the swing in its vertical position, and have the portions B³ B³ at an angle to B'' and B⁴ B⁴ parallel to B'', but at an angle to B³ B³, downwardly-bent portions B⁵ B⁵, and return bent portions B⁶ B⁶, laterally-extended portions B⁷ B⁷, having loops B⁸ B⁸ underneath the table, thereby forming a spring-clamp for attaching the swing to the table and causing it to retain its upright position. The swing is formed of two wires F E, bent in the form of a pendent loop, attached to top B' at their upper ends and held in contact by bands G' G, and separated below bands G' to form the seat F. Bands G' may be permanently attached, but bands G are loose and free to move on the wires. The

top B' has two bends where the top of the swing is attached.

When used as a doll-swing, the doll is seated upon the seat, bands G may be slid upward, the wires F E separated above G', and the arms of the doll inserted between the wires between the bands. Bands G, being then slid downward, bind the arms of the doll in the swing in the natural position.

What I claim, and desire to secure by Letters Patent, is—

1. In a toy swing, and in combination with a swinging frame, a stationary frame for the swinging frame, composed of a wire having a rectangular upright portion in which the swing vibrates, and at the foot thereof a laterally-projecting foot portion bent to form a spring-clamping device for attaching the same to a board or table, substantially as set forth.

2. In a toy swing, in combination with a suitable supporting-frame, a swinging frame, attached to the supporting-frame, composed of the paired rods E and F, separated at their lower end to form a seat and provided with bands G' G' and G G, arranged substantially as described, and for the purposes set forth.

3. In a toy swing, a stationary frame composed of wire, consisting of a rectangular upright frame within which the swinging frame is suspended to vibrate freely and provided with an integral laterally-projecting foot consisting of the branching portions B³ B³ B⁴ B⁴, downwardly-bent portions B⁵ B⁵, rearwardly-bent portions B⁶ B⁶, and laterally-bent portions B⁷ B⁷, provided with loops B⁸ B⁸, whereby said foot portion forms a spring-clamp for supporting the said frame in its vertical position, substantially as set forth.

In testimony whereof I affix my signature in presence of two witnesses.

DAVID L. KEELER.
